(57) **CLAIM**

I claim the ornamental design for the apparatus for covering a used syringe needle, as shown and described.

DESCRIPTION

FIG. 1 is a front elevational view of apparatus for covering a used syringe needle, showing my new design, the covers are shown in the open position, the rear view thereof being identical;

FIG. 2 is a top view thereof;

FIG. 3 is a bottom view thereof;

FIG. 4 is a right side elevational view thereof taken from FIG. 1, the left side elevational view thereof being identical;

FIG. 5 is a perspective view thereof; and,

FIG. 6 is a perspective view thereof but showing the covers in the closed position.

1 Claim, 2 Drawing Sheets

FIG. 2

FIG. 1

FIG. 4

FIG. 3

FIG. 5

FIG. 6
